COMBINED FOLDING TABLE SET AND STAND THEREFOR

John J. Keal, Los Angeles, Calif., assignor to Brown-Saltman Furniture Co., South Gate, Calif., a corporation of California

Application April 6, 1955, Serial No. 35,379

Term of patent 14 years

(Cl. D33—19)

Fig. 1 is a front perspective view of a combined folding table set and stand therefor, the opposite side of the stand and the back being the same in appearance as the side shown.

Fig. 2 is a front elevational view thereof with one table removed for purposes of illustration.

Fig. 3 is a top perspective view of one of the table members in folded position.

Fig. 4 is a perspective view of the table in Fig. 3 in open position.

The dominant features of the design reside in the portions shown in full lines.

I claim:

The ornamental design for a combined folding table set and stand therefor, substantially as shown and described.
